HOLDER FOR CUTLERY

Austin H. Munson, Arlington Heights, Ill., assignor to Ekco Products Company, Chicago, Ill., a corporation of Delaware

Filed Mar. 4, 1964, Ser. No. 78,868

Term of patent 14 years

(Cl. D44—29)

FIG. 2

FIG. 4

FIG. 1 is a front elevational view of a holder for cutlery showing my new design;

FIG. 2 is an elevational view thereof when the holder is rotated clockwise 90 degrees from the position of FIG. 1, with a portion shown in vertical section;

FIG. 3 is a top plan view thereof; and

FIG. 4 is a bottom plan view with a portion broken away for convenience of illustration.

I claim:

The ornamental design for a holder for cutlery, as shown and described.
